UNITED STATES PATENT OFFICE.

ALFRED I. CONE, OF NEW YORK, N. Y., AND CHARLES A. DARIUS, OF MONTCLAIR, NEW JERSEY; SAID CONE ASSIGNEE TO SAID DARIUS.

SPRING-OPERATED SELF-CLOSING RECEPTACLE.

Application filed January 6, 1926. Serial No. 79,507.

This invention relates to certain new and useful improvements in spring-operated self-closing receptacles of the type having a stationary perforated top wall or inner cover 5 upon which is superimposed a perforated rotatable cover, which latter cover may be manually rotated so as to cause openings in both the covers to register and thus to open the receptacle for receiving or discharging material, but which, when the manual pressure is released, will, through the operation of a spring, return to its normal position of closure, by throwing the openings out of register.

15 One of the objects of the invention is to provide improved spring-operating means and improved means for positioning the spring in such a self-closing receptacle, and to generally simplify the spring-operated 20 mechanism and the construction thereof so that the parts may be assembled economically and, to a large extent, mechanically.

Additional objects, advantages and features of the invention are inherent in the 25 novel construction, arrangement, and combination of the parts, as will be better understood from the following more detailed description and the accompanying drawings and claims.

30 These drawings, wherein like reference characters represent corresponding parts throughout, present the following views:

Figure 1. A fragmentary perspective view showing side and top of a receptacle 35 constructed in accordance with the present invention.

Figure 2. A top plan view of the outer rotatable cover showing perforations therein, and showing by dotted lines openings in the top wall or inner cover which is shown in the top plan view in Figure 3, and indicating a preferred position of the means in the outer cover by which the closure-operating spring is engaged.

45 Figure 3. A top plan view of the top wall or inner cover of the receptacle which is non-rotatably attached to the side walls, showing a depression therein in which the closure-operating spring, shown in Figure 5, is sunk and the means whereby the said spring is held in normal position by narrowing the said depression at the center, in one of the adaptations of the principle of the invention.

Figure 4. A top plan view of the stationary top wall or inner cover of the receptacle indicating another adaptation of providing means for holding the operating spring in normal position, in accordance with the general principle of the invention.

Figure 5. A vertical sectional view, taken on the line $v-v$ of Figure 4 in which the form of operating spring, illustrated in Figure 6, is shown in normal position, sunk into and standing on edge in the depression shown in Figure 4, along the longitudinal direction of the same, between the stationary top wall or inner cover and the outer rotatable cover, and indicating the means whereby the said spring is held in normal position with respect to the top wall or inner cover of the receptacle in accordance with the adaptation illustrated in Figure 3, and means whereby the rotatable cover is engaged toward the ends of the spring.

Figure 6. A preferred form of a spring, the general side plane contour of which is here made to correspond approximately with the form of a cross-section of the space between the two covers, along the longitudinal direction of the said depression, and which spring, when placed in position between the two covers shown in Figure 2 and in Figure 3 or 4, is engaged by the holding means provided by the stationary top wall or inner cover and the spring-engaging means provided by the rotatable outer cover in the manner illustrated in Figure 5.

The receptacle constructed in accordance with the invention herein described may be 90 made of any preferred design or general form of outline as may be best suited for the particular purpose for which it may be intended, and it may be constructed of any desired material which is suitable for 95 a vehicle of the material to be contained therein. In general, it may be stated that, for the smaller receptacles used for holding and dispensing toilet powders and the like, which are used in large numbers and which 100 are thrown away after they have been once emptied and where the cost of construction is a factor to be considered, the body of the receptacle may be made of a paper stock or fibroid and the covers may be stamped 105 out of a soft metal material such as tin, nickel-zinc or nickeloid, for instance, which are very pliable and can be readily stamped

or pressed into the required forms and which can also be readily crimped upon the open ends of the fiber body of such a canister, if that form of construction is desired.

The particular embodiment of the present invention as illustrated in the drawings is a form of shaker receptacle which is more especially adapted for holding and dispensing toilet powders such as talcum, zinc stearate, or the like.

The upper end of the receptacle is provided with a top wall or inner cover 9, as shown in Figures 3 and 4, which is fixedly or non-rotatably attached at its outer margin to the upper end of the receptacle body 1.

A depression, as exemplified in Figures 3 and 4 by 5 and 5' respectively, is stamped, pressed, or otherwise formed, in this top wall or inner cover 9, which depression 5 or 5' may have the general outline as shown in Figure 3 or in Figure 4, or any other general form of outline as may be suitable for the particular receptacle to be constructed and the material from which the top wall or inner cover may be made. When a highly ductile or easily moldable material is used, which will readily lend itself to pressing, stamping, or molding into any shape, the hour-glass form of depression, as shown in Figure 3, is preferable for more economically providing the holding means 6 for the spring 7. This adaptation is also to be preferred when it is desired to have a larger area of contact between the inner aspect of the outer rotatable cover 2 and the top wall or inner cover 9, and to permit a greater number of registrable perforations to be made in the contacting covers. In the hour-glass form of depression 5, as shown in Figure 3, the means for holding the spring 7 in operative position is provided by the side walls 6 of the narrow part of the depression. Otherwise the general outline of depression in the top wall 9 may be made in any suitable or convenient form, as, for instance, in the form as shown in Figure 4.

The depressions 5 and 5' as illustrated in Figures 4 and 5, it will be understood, represent broadly extremes of a number of possible utilitarian adaptations as to the outlines of the side walls of the depression. For instance, these side walls may be curved so as to conform substantially to the curve of the spring 7 when fully tensed, and this curvature will depend upon the strength of the spring, the relative positions of the spring-holding means, 6, 6', of the top-wall or inner cover 9 and the position of the spring-engaging means, 8, of the outer rotatable cover 2 relative to the said holding means 6, 6', in the top wall or inner cover, and to the extreme end of the spring 7. It is clear therefore that many adaptations of the principle of this invention may be em-

ployed with respect to the form of the depression, 6, 6', without departing from the spirit thereof.

The important novel feature of the present invention lies in the combination of the two contacting covers 2 and 9, the outer one 2 being rotatable with respect to the inner one 9, and the body of the container 1, a radial, diametral, or transverse depression, 5, 5', in the inner cover sufficiently deep to hold the actuating spring 7 substantially in the position as illustrated in the Figure 5, means 6 or 6' for receiving and holding the said spring 7 in normal position along the longitudinal direction, e. g., $v-v$ of the depression 5, 5', and means 8 for engaging at least one of the movable ends of this spring with the rotatable cover 2 so that, when the latter is rotated, lateral pressure will be exercised upon the said spring 7 by a manual rotating force applied to the rotatable cover and so that the rotatable cover will be caused to return to the normal position of closure when this manual pressure is relieved, through the lateral tension of the spring 7.

In the best adaptation of the principle of the invention, the width of the depression 5, 5', at the end nearest the margin of the cover should be such as to allow enough amplitude of motion for the rotatable cover 2 and the actuating spring 7 to permit the openings 3 and 4 of the two covers to register perfectly. It will be readily seen that this amplitude of rotation will be limited by the width of the outer end or ends of the depression wherein the movable end of the spring and the spring-engaging means in the rotatable cover move to and fro and come in contact with the walls of the depression.

In the adaptation illustrated in Figure 4, the means for holding the spring in normal position consists of a set of upwardly projecting pins or pegs 6' firmly anchored in the depressed portion of the top wall or inner cover. Similarly the outer or rotatable cover is provided with downwardly projecting pins or pegs 8 in such relative position that when this outer rotatable cover is placed in its proper position upon the receptacle and rotated the spring will be tensed laterally.

For the purpose of facilitating the assemblage of the parts, and to insure greater accuracy in bringing the parts into proper relation, especially when the work of assembling is done by mechanical means, for instance, the following additional features of construction as to the plane contour of the spring 7, as to the means 6 or 6' for receiving and holding the same in position within the depression of the top wall or inner cover 9, and as to the means 8 for engaging it with the outer or rotatable cover 2, are to be noted. The spring 7 may be made of any suitable thickness and width and in any

form that is adapted to be held in normal position by the holding means 6, 6', of the top wall or inner cover and to be positively engaged by the means provided for that purpose on the inner aspect of the outer cover, but the preferred form 7, illustrated in the drawing, has a contour conforming substantially to the outline of the longitudinal cross-section of the space formed between the two covers 2 and 9 occupied by it, with the ends thereof bevelled so that it may easily slide into position when dropped by gravity into the depression on edge. Also, to facilitate the reception of the spring when so deposited each pair of pins or pegs 6' is preferably made to diverge somewhat at the free ends thereof. Similarly, the narrow part of the depression 6, when the holding means in the top wall or inner cover is employed, substantially as illustrated in Figure 3, is made slightly wider at the top, so that the lower edge of the spring 7 will more readily drop into its normal position within the confines of the narrow channel 6. The plane contour of the spring is preferably made to conform to the outline of the longitudinal cross-section of the space formed by the depression 5 or 5' and the outer cover 2 in order to give to the spring the maximum of power to hold it more snugly in place. And so also the downwardly extending pegs 8 anchored on the inner aspect of the outer rotatable cover are slightly diverged at the free ends thereof to facilitate proper engagement of the upper edge of the spring by the outer rotatable cover when the same is placed in position on the top of the receptacle.

These detailed features are not essential for making the device effective for its major objects, as will be apparent from the description of the invention herein, but involve refinements of construction for the purposes stated.

It will thus be seen that when the parts are suitably assembled, the closure-actuating spring 7 is snugly housed within the space between the two covers 2 and 9 without interfering with their close contacting at all other points, and also without itself coming into contact with the substance contained within the body of the receptacle, thus permitting the free functioning of the spring without any clogging to prevent the spring from returning to its normal position when the pressure thereon is released.

It is evident that the depression 5 or 5' may be made relatively deep or shallow, depending upon the requirements of the particular construction, such as the amount of spring power required. It will also be apparent that the number of registrable openings of the two covers may be varied as required. In the particular embodiment of the invention as illustrated in the drawings, the outer cover is shown to have two openings

more than the number of those in the top wall or inner cover, permitting all the openings in the latter to register with an opening in the former irrespective of the direction in which the cover 2 is rotated, manifestly this detail of the construction may also be readily altered in such a manner that the openings can be made to register only by rotating the outer cover in one direction only. This it will be readily understood can be easily accomplished by altering somewhat the normal position of the spring 7 with respect to the limiting margins of the channel or depression in the top wall or inner cover, or by narrowing the width of one or the other side of the depression so as to decrease the amplitude of the possible movement of the spring and the rotatable outer cover in one direction.

Obviously also the top wall may be a fixed part of the receptacle, firmly soldered or clamped to the side walls, or it may be removably attached to such side walls in the form of a cover so long as it is not rotatable.

Obviously also the length of the closure-operating spring 7 may be varied relative to the diameter of the covers and so also the means for holding the spring in its normal position with respect to the fixed top wall or inner cover may be positioned more or less off center and away from either end of the operating spring. Furthermore, it is clearly not necessary that more than one end of the spring 7 be engaged by the rotating cover. However, to insure more positive action by the spring it is more desirable to engage both ends as illustrated in the drawings.

Obviously also other various changes or modifications in the details of structure or arrangement of the parts may be made without departing from the spirit and scope of the present invention, and it is also to be understood that the specific forms and arrangements as shown in the drawings and the special examples of the adaptation of the principle of this invention to one particular form of receptacle or canister are given by way of illustration and not by way of limitation. It is believed that the construction and operation of the device will now be fully understood from the foregoing description, and it is intended that various changes in mere detail of construction are contemplated as will fall within the scope of the invention as hereinafter claimed.

What is claimed as new is:

1. A self-closing receptacle comprising a container body, a non-rotatable top wall or inner cover having a downward depression running along a transverse line thereof, a rotatable outer cover superimposed upon and contacting with said top wall or inner cover, both of said covers being perforated, the perforations being so disposed that they can be caused to register by the rotation of the

6 said outer cover with respect to the said top wall or inner cover; a spring held in normal position by holding means within the said depression in the top wall or inner cover, and means attached to the rotatable outer cover for engaging at least one free end of said spring.

10 2. A self-closing receptacle comprising a container body, a non-rotatable top wall or inner cover having a downward depression running along a transverse line thereof, a rotatable outer cover superimposed upon and contacting with said top wall or inner cover, both of said covers being perforated, the 15 perforations being so disposed that they can be caused to register by the rotation of the said outer cover in either direction with respect to the said top wall or inner cover; a spring held in normal position by holding means within the said depression in the top wall or inner cover, and means attached to the rotatable outer cover for engaging at least one free end of said spring.

20 3. A self-closing receptacle comprising a container body, a non-rotatable top wall or inner cover having a downward depression running along a transverse line thereof, a rotatable outer cover superimposed upon and contacting with said top wall or inner cover, both of said covers being perforated, the 25 perforations being so disposed that they can be caused to register by the rotation of the said outer cover with respect to the said top wall or inner cover; a flat spring held in normal position on edge by holding means within the said depression in the top wall or inner cover, and means attached to the rotatable outer cover for engaging at least one free end of said spring.

30 4. A self-closing receptacle comprising a container body, a non-rotatable top wall or inner cover having a downward depression running along a transverse line thereof, a rotatable outer cover superimposed upon and contacting with said top wall or inner cover, both of said covers being perforated, the 35 perforations being so disposed that they can be caused to register by the rotation of the said outer cover with respect to the said top wall or inner cover; a flat spring held in normal position on edge by holding means within the said depression in the top wall or inner cover, and means attached to the rotatable outer cover for engaging at least one free end of said spring, the said spring having a plane contour conforming substantially to the configuration of a cross-section of the space between the said covers occupied by it.

40 5. A self-closing receptacle comprising a container body, a non-rotatable top wall or inner cover having a downward depression running along a transverse line thereof, a rotatable outer cover superimposed upon and contacting with said top wall or inner cover,

5 both of said covers being perforated, the perforations being so disposed that they can be caused to register by the rotation of the said outer cover with respect to the said top wall or inner cover; a flat spring held in 70 normal position on edge by holding means within the said depression in the top wall or inner cover, and means attached to the rotatable outer cover for engaging at least one free end of said spring, the said spring 75 being bevelled downwardly at least at one end thereof.

6. A self-closing receptacle comprising a container body, a non-rotatable top wall or inner cover having a downward depression running along a transverse line thereof, a rotatable outer cover superimposed upon and contacting with said top wall or inner cover, both of said covers being perforated, the 80 perforations being so disposed that they can be caused to register by the rotation of the said outer cover with respect to the said top wall or inner cover; a flat spring held in normal position on edge by holding means within the said depression in the top wall or inner cover, and means attached to the rotatable outer cover for engaging at least one free end of said spring, the said spring 85 being bevelled downwardly at least at one end thereof.

7. A self-closing receptacle comprising a container body, a non-rotatable top wall or inner cover having a downward depression running along a transverse line thereof, a 100 rotatable outer cover superimposed upon and contacting with said top wall or inner cover, both of said covers being perforated, the perforations being so disposed that they can be caused to register by the rotation of the said outer cover with respect to the said top wall or inner cover; a flat spring held in normal position on edge by holding means within the said depression in the top wall or inner cover, and means attached to the rotatable outer cover for engaging at least one free end of said spring, the said spring 95 engaging means of the rotatable outer cover at least consisting of downwardly diverging tines straddling the upper edge of the spring.

8. A self-closing receptacle comprising a container body, a non-rotatable top wall or inner cover having a downward depression running along a transverse line thereof, a 105

rotatable outer cover superimposed upon and contacting with said top wall or inner cover, both of said covers being perforated, the perforations being so disposed that they

can be caused to register by the rotation of the said outer cover with respect to the said top wall or inner cover; a flat spring held in normal position on edge by holding means within the said depression in the top wall or inner cover, and means attached to the rotatable outer cover for engaging at least one free end of said spring, the said spring 110

engaging means of the top wall or inner cover being formed by narrowing side walls of the said depression into which the spring 115

has been sunk.

8. A spring-operated self-closing shaker receptacle comprising a container body with a non-rotatable top-wall or inner cover, having a downward depression or channel running along a transverse line thereof, and a rotatable outer cover superimposed upon and contacting with said top wall or inner cover, both of said covers being perforated, both sets of perforations lying normally in a position of closure, but being so disposed that some of the perforations at least can be caused to register by the rotation of the said outer cover with respect to the said top wall or inner cover; an operating spring, lying 120

125

130

within the said transverse depression, and being held in normal position for closing the receptacle by holding means provided within the said depression or channel; means attached to the outer rotatable cover for contacting with the said spring at a different point thereof; the said spring, the said spring-contacting means attached to the ro-

tatable cover, and the limiting side wall of the said depression or channel being so disposed with reference to each other as to limit the amplitude of motion of the outer rotatable cover and the spring.
